UNITED STATES PATENT OFFICE.

CARBON P. DUBBS, OF WILMETTE, ILLINOIS, ASSIGNOR TO UNIVERSAL OIL PRODUCTS COMPANY, OF CHICAGO, ILLINOIS, A CORPORATION OF SOUTH DAKOTA.

PROCESS OF TREATING OILS.

1,411,961.

Specification of Letters Patent.

Patented Apr. 4, 1922.

Application filed April 16, 1917. Serial No. 162,233.

To all whom it may concern:

Be it known that I, CARBON P. DUBBS, a citizen of the United States, residing in the city of Wilmette, county of Cook, and State of Illinois, have invented certain new and useful Improvements in Processes of Treating Oils, of which the following is a specification.

The art of cracking petroleum hydrocarbons to form light hydrocarbons has become exceedingly active in the last few years. This is due primarily to commercial necessities confronting oil refiners. The constantly and rapidly increasing consumption of gasoline, the fact that the production of crude petroleum oil has not increased proportionately, the relatively high prices obtained for gasoline and the relatively low prices obtained for the other refined products, coupled with the increasing price of crude oil has forced the oil refiners, particularly the so-called independent refiners to be constantly striving to find some process which will commercially convert the heavier hydrocarbons into lighter hydrocarbons, particularly those of the gasoline series.

The most successful attempts so far to produce the desired result have been by pressure processes in which pressure is maintained on both the still and the condenser by means of the generated vapors. The present invention is an improvement on processes of this character.

Among the salient objects of the present invention are to provide a process in which the oil is circulated through the heated zone so as to subject it to the action of uniform heating for a maximum period of time, while, at the same time, permitting the vapors to pass freely to the condenser; to provide a process in which the danger due to local overheating arising from carbon deposits in the apparatus is obviated by causing the carbon to be precipitated and deposited at points remote from and outside of the heated zone of the combustion gases; to provide a process which can be run either as a continuous process or as a batch process and if desired, in the same apparatus; to provide a process in which a relatively rapid circulation of the oil through the heating zone is obtained, preferably by convection; to provide a process in which the partially converted vapors are condensed and returned to the heating zone; to

provide a process in which the incoming fresh oil is preferably preheated by means of the outgoing vapors acting in effect as a heat interchanger; to provide a novel apparatus for carrying out the improved process and in general to provide an improved process and apparatus of the character referred to.

In the drawings:

Fig. 1 is a side elevation of my improved apparatus suitable for carrying out the process.

Fig. 2 is a side elevation of the still on an enlarged scale with parts broken away and shown in section to bring out details of construction.

Fig. 3 is a side elevation of the front end of the condenser on an enlarged scale, the view of the condenser being taken at right angles to that shown in Fig. 1 and also showing the receiving tank.

Fig. 4 is a top plan view of the bulk supply drums and pipe connections.

Fig. 5 is a fragmentary end view of the construction shown in Fig. 4.

Referring to the drawings: 1, 2, 3 and 4 designate the supply drums which may be of any suitable number and are preferably of the horizontal boiler type. 5 designates the furnace of any suitable construction, within which is mounted the still proper designated as a whole 6. This still or retort consists of a cylindrical upper drum or receiver 7 and a pair of lower drums 8 and 9, the upper and lower drums being connected by means of tubes 10, which are fitted in suitable heads in the drums in a well known manner. The tubes which extend into the drum 8 are separated from the tubes leading to the drum 9, by a fire arch or bridge wall 11. The arrangement is such that the gases of combustion from the fire box of the furnace 5 are compelled to pass up over the bridge wall and down to the bottom of the stack 12. The stack is controlled by suitable dampers 13. The lower drums 8 and 9 are provided with hand hold plates 14, so that they can be cleaned out and the upper drum 7 is provided with a similar hand hold plate 15. The upper drum 7 also is provided with a gauge 16, liquid gauge 17, and safety valve 18. On the upper end of the drum 7 is mounted a combined reflux condenser and heat interchanger 19. The member 19 consists of upper and lower 110

headers 20 and 21 connected by tubes 22, through which the vapors pass, the lower header 21 being connected by pipe 23 to the drum 7. The headers are surrounded with 5 a shell 24. Incoming crude oil is admitted to the chamber 24 through the supply pipe 25 near the lower end of the chamber and is taken out near the upper end of the chamber through pipe 26. The pipe 22 leads to 10 a pump 27, which is connected through pipe 28 to any suitable source of supply such as an oil line or oil tank. The delivery pipe 26 leads to the manifold 29, which is connected by means of branch pipes 30 to the 15 front ends of the receiving drums 1, 2, 3 and 4. A valve 31 is interposed in the feed line 26 and similarly the branch feed pipes 30 are each provided with a valve 32 so that any one or more of the drums can be cut 20 out of the feed line.

The oil may be delivered from the bulk supply or receiving drums through the retort either by taking the oil out of the top of the drums or out of the bottom of the 25 drums. Describing first the manner of taking the oil out of the top of the drums which can be done in the event that the process is operated as a continuous process, i. e., with a constant supply of fresh oil being fed to 30 the drum a pipe 33 leads from the top of each drum and connects to manifold pipe 34, which is in turn connected to the lower end of the drum 8, through pipes 35 and 36. Describing the manner in which the oil is 35 taken from the lower end of the supply drums and delivered to the retort, which must be done in the event the process is operated as a batch process, pipes 37 extend down into each drum near the bottom as 40 shown more clearly in Fig. 1 and are connected to the manifold 34 and thus lead to the drum 8 through the same pipes 35 and 36. The pipes 33 are provided with valves 38 and the pipes 37 are similarly provided 45 with valves 39, it being obvious that when the valves of the pipes 33 are open, the valves of the pipe 37 are closed, and vice versa.

Describing now the manner in which the 50 oil is circulated from the retort back to the drums, a return pipe 40 connects to a return manifold 41, and from this manifold 41 return pipes 42 lead to the front end of the drums 1, 2, 3 and 4. Valves 43 are 55 interposed in the return pipes 42 whereby any pipe may be cut out. From the foregoing it will be seen that whether the oil is taken from the top or bottom of the supply drums, 1, 2, 3 and 4, it is circulated from the supply tank through the drum 8, tube 10, drum 7, tube 10, drum 9 and back to the supply tanks through the by-way of the manifold 41 and return pipes 42. From the foregoing 60 it will also be seen that the supply tanks are connected in multiple.

When the process is operated as a continuous process, means must be provided for continuously removing the heavy residuum from the supply drums 1, 2, 3 and 4. This is accomplished by means of the header 44, 70 which is connected to the rear ends of the drums about midway their height by means of branch pipes 45, controlled by valves 46, 47 and 48. The object of having the triple sets of valves is that by shutting the valves 46 and 48 on any supply drum and opening the valve 47, on said supply drum, this supply drum is cut out and by-passed. By opening the valves 46 and 48 and closing the valve 47 the supply drum is admitted into 80 the series.

In certain instances, it may be desirable to connect the supply tanks in series instead of in multiple so as to form in effect, one large supply tank. This is accomplished as 85 follows: The valves 43 in the pipes 42 leading to drums 1, 2, and 3 are shut. The valve 43 in the pipe 42 leading to drum 4 is left open. Valves 46 and 47 on drum 4 are closed. Valve 48 on drums 4 is left open. Valves 46 and 48 on drums 2 and 3 are left open while valves 47 in drums 2 and 3 are closed. Valve 46 in drum 1 is left open while valves 47 and 48 are closed. The circulation is then 95 as follows:

The oil is introduced from suction line 28 to pump 27 and discharged through line 22 into and through reflux condenser 19 and withdrawn from there through line 26. Thence the oil passes into manifold 29 and 100 by branch pipes 30 to the front end of the receiving drums. The oil is drawn from these drums (or as many of them as are then open into the system) through pipes 33 (if a continuous process is being used) or 105 pipes 37 (if a batch process is being used) to manifold 34 and back by pipes 35 and 36 to bottom of drum 8. From drum 8 oil flows through the tubes to the drum 7 and then back through the adjacent tubes to 110 drum 9. From drum 9, the oil goes through outlet 40 to manifold 41 and back to the supply drums.

Where the process is operated as a continuous one, the drums 1 and 2, 3 and 4 are 115 kept practically full. To prevent the gas pocket which is usually formed in the drums, each is provided with an outlet 49, leading to manifold 50, each pipe 49 having a valve 51. The manifold 50 leads to any suitable 120 storage.

From the top of the header 20 of the reflux condenser, a pipe 52 leads to a water condenser 53, the latter being mounted in a suitable water tank 54. The coils of the 125 condenser 53 are so positioned as to have a gradual incline downwardly to the receiving tank 55. Water is supplied to the tank 54 by means of supply pipe 56 having a valve 57. The tank 54 also has a water over- 130

flow pipe 58. In the pipe 52 is interposed valve 59. The receiving tank 55 has a safety valve 60, pressure gauge 61, glass liquid gauge 62, and gas blowoff pipe 63, controlled by valve 64. The lower end of the receiving tank 55 has a distillate discharge line 65, controlled by valve 66. Preferably a water drawoff 67 is provided having a valve 68. From the foregoing it will be seen that pressure can be maintained on both the still and condenser and regulated by means of valves 64 and 66; at the start of the process, to get up initial pressure, the valve 59 may be closed. The reflux condenser is provided with pressure gauge 69 and the pipe 52 with a pyrometer 70. The receiving tanks are also provided with water gauges 71, to show the level of the liquid in the drums.

The operation of the process is as follows: 20 Oil, whether it be crude petroleum, distillate or residuum is pumped into the receiving drums which are connected either in multiple or in series as may be desired in sufficient quantity to fill the latter up to the 25 level designated by line A in the drum 7. As the oil in the retort is heated, the vapors will pass up through the reflux condenser and thence over into the receiving tank through the gooseneck and water condenser. 30 The heavier or partially converted vapors will be condensed in their passage through the reflux condenser and will fall back into the retort and be again subjected to the cracking action. The incoming crude oil 35 acts as a condenser to return these heavier vapors to the retort. If the process is operated as a batch process the reflux condenser can either be used as an aerial condenser or it can be cooled in some other suitable manner. 40 The unvaporized oil which passes through the retort is, of course, returned to the drum and again delivered to the retort and can be subjected to the heat of the cracking action. In practice, this circulation 45 takes place very rapidly so that the oil is subjected to the heating action for relatively prolonged periods. The receiving tanks are preferably insulated and the circulation is so rapid that the oil in passing 50 from the lower end of the retort back to the drums is only slightly cooled. It is necessary that it be cooled somewhat in order to get a rapid circulation. The temperature and pressure varies with the character of the 55 oil being treated. A temperature of from 450 to 1000° F. is suitable and a pressure of from 80 to 250 pounds to the square inch will probably be ample.

As will be appreciated by those skilled in 60 this art, there will be formed in the oil under treatment in the heating tubes numerous carbonaceous particles, insoluble in the oil in which they are formed and of heavier gravity than the oil, which have a tendency to adhere to any metallic surfaces with

which they may contact, and the adhering of these particles to the walls of the heating tubes seriously militates against the efficient operation of the apparatus.

In my described process this detrimental action is obviated, or greatly lessened. These carbonaceous particles in carrying out my process tend to move in a direction substantially parallel with the walls of the heating tubes, and there is thus no chance for the particles to settle upon such surfaces, as occurs when the heating tubes are horizontally arranged, or arranged approximately in a horizontal position. Moreover, the sweep of the oil through the tubes tends to prevent the adherence of the particles to the walls of the tube.

In my process, as hereinbefore described, certain of the carbonaceous particles will be carried along by the upward flowing streams of oil in the front battery of tubes, and a majority of such particles will be deposited in the upper header, or drum 7, about the ends of the tubes. The other particles separated from the oil in the heating thereof will for the most part find lodgment in the lower drums 8 and 9.

In my process, as hereinbefore described, the movement of the vapors generated in the heating tubes is retarded only to a minimum extent by frictional contact with the walls of the heating tubes, since these walls are disposed substantially parallel to the direction of movement of such vapors.

I claim as my invention:

1. The described process for cracking oil, consisting in effecting the passage upwardly in a battery of substantially vertically disposed tubes of a part of a body of oil, during which the temperature of the oil is raised sufficiently to crack a substantial part thereof, discharging the heated oil from the upper ends of the tubes into a relatively large receiver, having a vapor space above the level of the oil therein, taking off from the receiver the products of vaporization, controlling the discharge of the latter for imposing a substantial pressure on the oil under treatment, and returning to the lower ends of the tubes from the receiver the unvaporized oil for further heating in said tubes.

2. The described process for cracking oil, consisting in effecting by convection the passage upwardly in a battery of substantially vertically disposed tubes of a part of a body of oil, during which the temperature of the oil is raised sufficiently to crack a substantial part thereof, discharging the heated oil from the upper ends of the tubes into a relatively large receiver, having a vapor space above the level of the oil therein, taking off from the receiver the products of vaporization, controlling the discharge of the latter for imposing a substantial pres-

- sure on the oil under treatment, and returning to the lower ends of the tubes from the receiver the unvaporized oil for further heating in said tubes.
- 5 3. The described pressure process for cracking oil, which consists in providing a body of oil, having a relatively small portion located in a battery of small vertical tubes positioned in a heating zone, another 10 portion held as a pool above and in open communication with the upper ends of said tubes, and an additional portion between the pool and the lower ends of said tubes, effecting a cyclic circulation of said body of 15 oil for passing the same in small streams rapidly upwardly through said tubes, where it is heated to cause cracking, taking off the generated vapors from above said pool, and controlling the discharge of the vapors 20 for maintaining a substantial pressure on the body of oil under treatment.
4. The described pressure process for cracking oil, consisting in maintaining a body of oil, with a portion located in a battery of vertical tubes, a portion arranged as a pool in free communication with the upper ends of the tubes, and a portion located between the pool and lower ends of the tubes, effecting a cyclic circulation of 25 said oil to cause the same in relatively small portions to flow upwardly through said tubes, wherein it is heated to a temperature between 400° to 1900° F., taking off from the oil in the pool the generated vapors, condensing the condensable portions thereof, and controlling the discharge of the vapors for producing a pressure thereof upon the body of oil between 80 to 250 pounds to 30 the square inch.
- 40 5. The described process for cracking oil, which consists in providing a body of oil with a relatively small portion thereof held in a battery of vertical tubes, located in a heating zone, a second portion held in a 45 second battery of tubes, located in said heating zone and more remote from the source of heat than the first battery, another portion of said body of oil being held as a pool above and in open communication with the 50 two batteries of tubes, and having a vapor space above the same, and an additional portion located between and in open communication with the lower ends of the two batteries of tubes, said body of oil being 55 given a cyclic circulation upwardly in relatively small quantities through the tubes of the first battery and downwardly through the tubes of the second battery, and the generated vapors being taken off from said

vapor space and condensed, and the discharge thereof controlled for imposing a pressure of the generated vapors upon the oil under treatment.

6. The described process for cracking oil, which consists in providing a body of oil 60 with a relatively small portion thereof held in a battery of vertical tubes, located in a heating zone, a second portion held in a second battery of tubes, located in said heating zone and more remote from the 65 source of heat than the first battery, another portion of said body of oil being held as a pool above and in open communication with the two batteries of tubes, and having a vapor space above the same, and an additional 70 portion held in a reservoir in open communication with the lower ends of the two batteries of tubes, effecting a cyclic circulation of the oil upwardly in the tubes of the first battery of tubes, and downwardly in the 75 tubes of the second battery, taking off the vapors from said vapor space, and condensing the same, and controlling the discharge of the vapors for imposing a pressure of the generated vapors upon the body of oil 80 under treatment, substantially as described.

7. A process of converting heavy into lighter hydrocarbons which consists in cracking the oil under a pressure in excess of 50 pounds to the square inch, causing the oil 90 to pass upwardly through vertical tubes seated in a furnace and thence to a vapor chamber, taking off the vapors from said vapor chamber and collecting and condensing them, returning the unvaporized oil 95 from said chamber vertically downwardly through a second set of tubes located in said furnace and thence to a reservoir located outside of the heating zone, returning the oil from the reservoir to the first set of vertical tubes and continuing said circulation during the process.

8. A process of converting heavy into lighter hydrocarbons which consists in cracking the oil under a pressure in excess of 50 pounds to the square inch, causing the oil 100 to pass upwardly through vertical tubes seated in a furnace and thence to a vapor chamber, taking off the vapors from said vapor chamber and collecting and condensing them, returning the unvaporized oil 105 from said chamber to a reservoir located outside of the heating zone and returning the oil from the reservoir to said vertical tubes and continuing said circulation during the process.

CARBON P. DUBBS.
